UNITED STATES PATENT OFFICE.

EMERY D. BLACKBURN, OF SAN FRANCISCO, CALIFORNIA.

HOSE-CLAMP.

1,344,433.

Specification of Letters Patent. Patented June 22, 1920.

Application filed April 10, 1919. Serial No. 289,057.

To all whom it may concern:

Be it known that I, EMERY D. BLACKBURN, a citizen of the United States, residing at San Francisco, in the county of San Francisco and State of California, have invented new and useful Improvements in Hose-Clamps, of which the following is a specification.

The present invention relates to improvements in hose clamps. It has been especially devised for the purpose of clamping leaky or cut hose used for supplying air from an air compressor to riveting or like tools.

The object of the invention is to provide a device by which the hose can be clamped very quickly and conveniently, thus economizing in compressed air, and which is readily adjustable for all sizes of hose.

In the accompanying drawing Figure 1 is a side view of the clamp in its extended position; Fig. 2 is a sectional view on the line 2—2 of Fig. 1; Fig. 3 is a sectional view on the line 3—3 of Fig. 1, showing the clamp in its operative position clamping an air hose.

Referring to the drawing, 1 indicates a bar, a mediate portion of which is straight and having at one end a short curved portion 2 and at the other end a curved long portion 3, for the most part in an arc of a circle about the other end of the bar as center. Said portion 3 is formed on one side with ratchet teeth 4. To the free end of the short portion 2 is pivoted, as shown at 5, the reduced end of a lever 6 which extends to one side of, and beyond, the curved portion 3 of the bar. The side of the lever 6 adjacent to the ratchet teeth 4 is reduced in thickness, as shown at 7, for a short distance, and the side of said lever 6 farthest from the straight portion of the bar is formed within an angular groove 8, the inner side of which is adapted, as shown in Fig. 2, to engage any one of the ratchet teeth 4. The pivot 5 is sufficiently loose to permit the lever 6 to be moved over said ratchet teeth to any position desired to engage a flexible pipe, the pressure of the pipe holding the bar against the nearest one of the ratchet teeth which are then on the side of said lever 6 remote from the straight portion of the bar.

Upon said straight portion can slide a saddle 9 having a convexly curved upper surface 1, and upon which can be laid a hose pipe 12. The lever 6 is then depressed

by pressing the foot on the free end thereof beyond the rounded portion 3 of the bar, compressing said hose pipe, and, when the foot is removed, it is retained in such position by engagement with one of the ratchet teeth 4.

The saddle 9 can be moved longitudinally along the bar 1 to vary its position for different sizes of hose, it being moved toward the rounded portion 2 when it is intended to clamp small hose and toward the rounded portion 3 for larger hose. It is held to the bar 1 by means of screws 13 which are screwed through the saddle and the pointed ends of which are received in grooves 14 in the sides of the bar 1.

I claim:

1. A clamp comprising a bar, one end of which extends transversely to the main portion of the bar and integrally therewith and has at a side thereof a series of ratchet teeth, a lever pivoted to the other end of the bar and extending beyond said transverse portion and having adjacent to said transverse portion a part adapted to engage any one of said ratchet teeth, and means on said bar between which and the lever a hose pipe can be clamped.

2. A hose clamp comprising a bar having a terminal portion extending transversely to its mediate portion, means upon which a hose to be clamped is placed slidably upon said mediate portion, and a lever pivoted to the other end of the bar, extending beyond said terminal portion and adapted to cooperate with said means to clamp a hose; and means on said transversely extending portion and said lever for locking the lever in clamping position.

3. A hose clamp comprising a bar having a straight mediate portion, a short curved terminal portion at one end and a comparatively long curved portion at the other end, the latter portion being provided with a series of ratchet teeth, a lever pivoted at the first-named end of the bar and extending beyond the curved portion of the other end and having a recess in the side next adjacent to said ratchet teeth and an angular groove, one side of which is adapted to engage a side of any one of said ratchet teeth to retain the lever in position, and a saddle slidable upon the straight portion of the bar.

4. A hose clamp comprising a bar having a straight mediate portion, a short curved

terminal portion at one end and a comparatively long curved portion at the other end, the latter portion being provided with a series of ratchet teeth, a lever pivoted at 5 the first-named end of the bar and extending beyond the curved portion of the other end and having a recess in the side next adjacent to said ratchet teeth and an angular groove, one side of which is adapted to en-

gage a side of any one of said ratchet 10 teeth to retain the lever in position, a saddle slideable upon the straight portion of the bar, the side of said saddle next adjacent to said lever being convexly rounded, and sides of the bar being longitudinally 15 grooved, and screws screwed through said saddle and entering said grooves.

E. D. BLACKBURN.
